UNITED STATES PATENT OFFICE

118,164

DESIGN FOR A COMBINED DISPLAY DEVICE AND MUSIC BOX

Raymond Loewy, New York, N. Y., assignor to Parfums Schiaparelli, Inc., New York, N. Y., a corporation of New York

Application September 1, 1939, Serial No. 86,995

Term of patent 7 years

To all whom it may concern:

Be it known that I, Raymond Loewy, a citizen of the United States, residing at New York, in the county of New York and State of New York, have invented a new, original, and ornamental Design for a Combined Display Device and Music Box, of which the following is a specification, reference being had to the accompanying drawing, forming part thereof.

In the drawing

Fig. 1 is a perspective view of a combined display device and music box showing my new design;

Fig. 2 is a sectional view along line 2-2 of Fig. 1.

I claim:

The ornamental design for a combined display device and music box, as shown.

RAYMOND LOEWY.
